BUCKLE

Milton Brock, Great Neck, N. Y.

Application May 5, 1955, Serial No. 35,816

Term of patent 7 years

(Cl. D17—1)

FIG. 1.

FIG. 2.

Fig. 1 is a front plan view of a buckle showing my new design.

Fig. 2 is a top edge view.

The dominant features of my design reside in the portion shown in broken lines, the side opposite that shown in Fig. 1 being substantially plain.

I claim:

The ornamental design for a buckle, substantially as shown and described.
